UNITED STATES PATENT OFFICE.

OZRO A. CRANE AND HENRY J. LEWIS, OF GREEN POINT, NEW YORK, ASSIGNEES TO
OZRO A. CRANE.

SCRAPER FOR REMOVING DIRT FROM BOOTS AND SHOES.

Specification of Letters Patent No. 12,660, dated April 3, 1855.

To all whom it may concern:

Be it known that we, Ozro A. CRANE and HENRY J. LEWIS, both of Green Point, in the county of Kings and State of New York, have invented, made, and applied to use certain new and useful Improvements in Scrapers for Removing Dirt from Boots, Shoes, &c.; and we do hereby declare that the following is a full, clear, and exact description of the same, reference being had to the annexed drawing, making part of this specification, wherein—

Figure 1, is a plan of the scraper complete. Fig. 2, is a vertical section of the same.

The like marks of reference denote the same parts.

The nature of our said improvement consists in attaching spring brushes in such a manner that while the bottom of the boot or shoe is scraped off on a metal scraper the sides and around the heel are cleaned off by the brushes conforming to the curve of the side of the boot or shoe, by means of the springs.

The metal scraper *a*, is secured to the desired place by screws 1, 1, passing through the bottom flange of the scraper, and *b*, *b*, are metal sides formed with the scraper and running at right angles or nearly so thereto. On the inner faces of these sides, lugs 2, 2, are formed, nearly on the level of the top of the scraper *a*, and each lug is provided with a stud or pin, entering the forward 35 end of the block *d*, which is provided with bristles *c*, *c*.

e, is a small bracket to each brush with a pin entering a hole in the brush block on a line opposite the stud 2, and this bracket *e*, is secured by means of a screw 3, passing through the bracket into the sides *b*, (see Fig. 3.) By this method of mounting, each brush *c*, can be turned horizontally on the joint at the end, and the brushes are to be forced toward each other by means of suitable springs (*f*.) acting between the sides *b*, and blocks *d*.

It will now be evident that the brushes being retained at their forward end, as the boot or shoe is drawn through, and the sole scraped on the scraper *a*, the heel is brushed off in the act of separating the brushes by passing between them; and as the foot is

drawn along, the hollows in the sides of the boot or shoe are brushed out, and the entire 55 sides of the boot brushed off clean. And it will be evident that a horizontal brush might be used behind the scraper to brush off the bottom of the sole.

We are well aware that stationary brushes 60 and scrapers have been used to brush off boots and shoes, but in order that the foot may have room to pass through, the brushes have to be so far apart that both sides cannot be brushed at the same time, neither 65 can the straight brushes ordinarily used be made to brush out clean, the hollows in the sides of the boot; hence we have attached the brushes in such a manner that they are kept against the sides of the foot, 70 whatever size or shape it may be; and although we believe that attaching each brush at or near one end is far the best for conforming to the shape of the foot, still the brushes might be attached at any other point 75 so long as the springs could force them together to act in the same manner.

In cases where this scraper is attached to an iron railing the side pieces *b*, may be made separately, and attached by clamps at 80 the sides of the fixed scraper in the railing.

The brushes *c*, being exposed to mud and dirt may become clogged; hence we have adopted the method herein shown of attaching the brackets *e*, so that by simply 85 unscrewing the same, the brushes may be removed cleaned and then replaced or new ones substituted.

What we desire to secure by Letters Patent is—

We claim the method herein described and shown of causing the brushes *c*, to accommodate themselves to any size or shape of boot or shoe, and brush off both sides at once, by so attaching said brushes that they 95 shall be forced together by springs, substantially as specified.

In witness whereof we have hereunto set our signatures this thirteenth day of January 1855.

OZRO A. CRANE.
HENRY J. LEWIS.
